UNITED STATES PATENT OFFICE.

WILLIAM F. RESCHKE, OF WICHITA, KANSAS.

DEVICE FOR EXTINGUISHING FIRES IN TANKS.

1,363,271.

Specification of Letters Patent. Patented Dec. 28, 1920.

Application filed November 7, 1919. Serial No. 336,323.

To all whom it may concern:

Be it known that I, WILLIAM F. RESCHKE, a citizen of the United States, residing at Wichita, in the county of Sedgwick and State of Kansas, have invented certain new and useful Improvements in Devices for Extinguishing Fires in Tanks; and I do declare the following to be a full, clear, and exact description of the invention, such as will enable others skilled in the art to which it appertains to make and use the same.

This invention relates generally to fire extinguishers, and more particularly to devices for extinguishing fires in tanks.

One object of the invention is to provide a device for extinguishing fires in oil tanks and the like consisting of a float adapted to float upon the oil contained in the tank and carrying a casing containing a fire extinguishing compound which is expelled by automatic means when a fire breaks out in the tank.

Another object of the invention is to provide a device of this class which is extremely simple, strong, durable and inexpensive in construction, one which will be efficient and reliable in operation, and well adapted to the purpose for which it is designed.

With these and other objects in view, the invention consists of the novel features of construction, and the combination and arrangement of parts as will be hereinafter fully described and claimed.

In the accompanying drawings in which similar reference characters designate like parts throughout the several views:

Figure 1 is a vertical sectional view through a portion of an oil tank, showing a device constructed in accordance with this invention floating upon the oil contained therein;

Fig. 2 is an enlarged vertical sectional view through the device; and,

Fig. 3 is a horizontal sectional view taken on the plane indicated by the line 3—3 of Fig. 2.

In the embodiment illustrated the numeral 1 designates a hollow metal float, which may be of any suitable configuration, but which is preferably circular. Mounted upon the upper side of the float 1 is a circular casing 2 having therein a central tube 3 extending from the top to the bottom thereof, horizontal partitions 4 and radial partitions 5 extending from the tube 3 to the upright wall of the casing 2. These partitions 5 are disposed

between the top of the casing 2 and the uppermost horizontal partition 4, the intermediate partitions 4 and the lowermost partition 4 and the top of the float 1, and the partitions of each set are disposed in staggered relation as shown in Fig. 1. The tube 3 is provided with openings which lead into the various cells formed by the partitions 5.

Disposed in each of the cells above referred to at their inner ends adjacent the tube 3 are charges 6 of explosive material, and disposed in the cells beyond the explosive charges 6 are charges of fire extinguishing compound 7. Arranged in the tube 3 is a fuse 8, the latter having its upper end extended a considerable distance above the upper end of the tube 3 and the casing 2 and unraveled as at 9 to make it readily inflammable. Short sections 10 of the fuse 8 extend through the openings in the tube 3 into the inner ends of the cells.

In using the device above described it or a number of them are placed upon the oil *a* contained in a tank *b* according to the size 80 of the tank. Should a fire break out in the tank the first flash is usually strong on account of the accumulated gases and the flame thus produced will ignite the unraveled end 9 of the fuse 8. When the fuse burns to the first tier of cells it will ignite the explosive charges 6 contained therein and explode, breaking away the adjacent portion of the casing 2 and scattering the fire extinguishing compound 7 contained in the cells in all 90 directions. The fuse 8 will continue to burn until all the tiers of cells are exploded and the fire extinguishing compound being scattered in all directions and throughout the 95 tank will extinguish the fire.

It is to be understood that the casing may be made in as many tiers as desired and that the various tiers may be divided into as many cells as desired. Other changes may 100 be made within the scope of the invention as defined in the appended claims.

What is claimed is:

1. A device of the class described comprising a casing having formed therein a 105 plurality of radial cells, charges of fire extinguishing compound disposed in said cells, explosive charges also disposed in said cells at the inner ends thereof for breaking said cells and scattering said charges of fire extinguishing compound, and an inflammable fuse carried by said casing and communi- 110

cating with the explosive charges through the inner ends of said cells, said fuse extending outside of said casing.

2. A device of the class described comprising a casing having formed therein a plurality of radial cells arranged in tiers, the cells of one tier being arranged in staggered relation with respect to the cells of the adjacent tier, charges of fire extinguishing compound disposed in said cells, explosive charges also disposed in said cells at the inner ends thereof for breaking said cells and scattering said charges of fire extinguishing compound, and an inflammable fuse carried by said casing and communicating with the explosive charges through the inner ends of said cells, said fuse extending outside of said casing.

3. A device of the class described comprising a casing, radially extending upright partitions disposed in said casing and dividing it into a number of radially extending cells, charges of fire extinguishing compound disposed in said cells, explosive charges also disposed in said cells at the inner ends thereof for breaking said cells and scattering said charges of fire extinguishing compound, and an inflammable fuse carried by said casing and communicating with said explosive charges through the inner ends of said cells, said fuse extending outside of said casing.

4. A device of the class described comprising a casing, horizontal partitions disposed in said casing, radially extending upright partitions disposed between said horizontal partitions and the latter and the top and bottom of said casing, whereby to form tiers of radially extending cells, charges of fire extinguishing compound disposed in said cells, explosive charges also disposed in said cells at the inner ends thereof for

breaking said cells and scattering said fire extinguishing compound, and a fuse carried by said casing and communicating with said explosive charges through the inner ends of said cells, said fuse extending outside of said casing.

5. A device of the class described comprising a hollow cylindrical casing, a tube disposed centrally in said casing, horizontal partitions disposed in said casing, radially extending upright partitions disposed between said horizontal partitions and the latter and the top and bottom of said casing, whereby to form tiers of radially extending cells, said tube being provided with apertures leading into the inner ends of said cells, charges of fire extinguishing compound disposed in said cells, explosive charges also disposed in said cells at the inner ends thereof for breaking said cells and scattering said charges of fire extinguishing compound, and an inflammable fuse disposed in said tube and having portions extending through said apertures into the inner ends of said cells, said fuse extending outside of said casing.

6. A device of the class described comprising a casing having arranged therein a plurality of radially extending cells, charges of fire extinguishing compound disposed in said cells, explosive charges disposed in said cells at the inner ends thereof for breaking said cells and scattering said charges of fire extinguishing compound, an inflammable fuse carried by said casing and communicating with the explosive charges through the inner ends of said cells, said fuse extending outside of said casing, and a float upon which said casing is mounted.

In testimony whereof I have hereunto set my hand.

WILLIAM F. RESCHKE.
